CLAIM

I claim the ornamental design for a knob, as shown and described.

DESCRIPTION

FIG. 1 is an upper perspective view of a knob showing my design.

FIG. 2 is a front view thereof;

FIG. 3 is a back view thereof;

FIG. 4 is a side view thereof;

FIG. 5 is an opposite side view thereof;

FIG. 6 is a top view thereof;

FIG. 7 is a bottom view thereof;

FIG. 8 is an upper perspective of a second embodiment of the knob shown in a reduced scale, the sole difference being the height;

FIG. 9 is an upper perspective of a third embodiment of the knob shown in reduced scale, the sole difference being the height;

FIG. 10 is an upper perspective view of a fourth embodiment of the knob shown in reduced scale, the sole difference being the height; and,

FIG. 11 is an upper perspective view of a fifth embodiment of the knob shown in reduced scale, the sole difference being the height.
